UNITED STATES PATENT OFFICE.

MINARD A. POSSONS, OF CLEVELAND, OHIO, ASSIGNOR TO AMERICAN STOVE COMPANY, OF ST. LOUIS, MISSOURI, A CORPORATION OF NEW JERSEY.

DESIGN FOR A GAS RANGE.

Application filed March 18, 1927. Serial No. 21,198. Term of patent 14 years.

To all whom it may concern:

Be it known that I, MINARD A. POSSONS, a citizen of the United States, residing at Cleveland, in the county of Cuyahoga and State of Ohio, have invented a new, original, and ornamental Design for Gas Ranges, of which the following is a specification, reference being had therein to the accompanying drawings.

The figure is a perspective view of the article showing my new design.

The distinctive feature of applicant's design consists in a gas range in which the doors of the oven and broiler are made with a flat front which are substantially in a plane with the edges of the oven.

I claim:

The ornamental design for a gas range as shown and described.

In testimony whereof, I hereunto affix my signature.

MINARD A. POSSONS.
